[57] CLAIM

The ornamental design for a storing and display container, as shown and described.

DESCRIPTION

FIG. 1 is a front perspective view of the base member of a storing and display container showing my new design, shown separately for clarity of illustration;

FIG. 2 is a perspective view of one of the two retaining walls, shown separately for clarity of illustration;

FIG. 3 is a front perspective view of the storing and display container;

FIG. 4 is a top view, of FIG. 1;

FIG. 5 is a front view of FIG. 1;

FIG. 6 is a left side view of FIG. 1;

FIG. 7 is a rear view of FIG. 1;

FIG. 8 is a bottom elevational view of FIG. 1;

FIG. 9 is an enlarged top view of the retaining wall, shown separately for clarity of illustration;

FIG. 10 is a front view of FIG. 9;

FIG. 11 is a right side view of FIG. 9;

FIG. 12 is a bottom view of FIG. 9;

FIG. 13 is a rear view of FIG. 9; and,

FIG. 14 is a perspective view of the storing and display container on a reduced scale, with two storing and display containers, their contents, and a shelf shown in broken lines for purposes of illustration only and forming no part of the claimed design.
